United States Patent Office

JOHN H. COOPER, OF PHILADELPHIA, PENNSYLVANIA, ASSIGNOR TO E. J. SPANGLER, W. E. LOCKWOOD, AND E. D. LOCKWOOD, OF SAME PLACE.

Letters Patent No. 62,939, dated March 19, 1867.

IMPROVEMENT IN ENVELOPE MACHINES.

The Schedule referred to in these Letters Patent and making part of the same.

TO ALL WHOM IT MAY CONCERN:

Be it known that I, JOHN H. COOPER, of Philadelphia, Pennsylvania, have invented certain Improvements in Envelope Machines; and I do hereby declare the following to be a full, clear, and exact description of the same, reference being had to the accompanying drawing, and to the letters of reference marked thereon.

My invention consists of certain mechanism, fully described hereafter, for making envelopes similar to those for which Letters Patent of the United States were granted to S. E. Petee, on the twenty-third day of March, A. D. 1859.

In order to enable others skilled in the art to make and use my invention, I will now proceed to describe its construction and operation, reference being had to the accompanying drawing, which forms a part of this specification, and in which—

Figure 1 is a vertical section of sufficient of an envelope machine to illustrate my improvements.

Figure 2, a plan view.

Figure 3, a transverse vertical section on the line 1 2, fig. 1.

Figures 4 and 5, views of detached portions of the machine.

Figures 6 and 7, diagrams illustrating my invention; and

Figure 8, an inverted view of the cross-head and its knives.

Similar letters refer to similar parts throughout the several views.

Two side-frames, A and A', support a table, B, to the under side of which are secured the four tubular guides *a* for the rods *b*, the latter being connected together at the bottom by the plate D, and at the top by the cutter plate or cross-head E. In an opening in the plate D turns a roller, *e*, which bears upon the periphery of a cam, F, on the driving-shaft G, the latter turning in suitable boxes or bearings on the opposite side-frames. In the cross-head E is an opening, through which projects the outer end of an arm, H, secured to the table B; this arm carrying two rollers, I I, which bear on rollers J J, secured to a shaft, K, which turns in the opposite side-frames. A pinion, *h*, loose on this shaft, gears into a wheel, *i*, on a shaft, L, which is also adapted to bearings on the opposite side-frames, and to this pinion is hung a spring-pawl, *g*, arranged to catch against projections, *r*, on the shaft K. On the shaft L is an arm, *k*, to which is connected a pin, *m*, rendered adjustable on the end of an eccentric-rod, *n*, which embraces the eccentric M. Two standards, N and N', are secured to the table B, near the front end of the same, and in these standards turns a spindle, *t*, carrying a roll of paper, which passes downwards in the direction shown by red lines, and between the rollers P and Q, the latter turning in permanent bearings in the standards N and N', and the former having upper sliding bearings, acted on by two spiral springs, *w w*, each of which is coiled round a rod contained in a vertical slot in each of the standards N and N', these springs having a tendency to force the upper roller P against the lower roller Q. After passing between these rollers the paper takes a downward and then an upward direction, thereby forming a loose fold, as illustrated in fig. 1, and then passes along the surface of the table beneath the bar *x*, over the bar *x'*, and beneath the bar *x''*, and finally between the drawing-rollers I and J, where it is acted upon by the knives of the cross-head E, in the manner described hereafter. Two guide plates, *v* and *v'*, are arranged to slide freely on the bars *x*, *x'*, and *x''*, the plate *v* being jointed to the long arm of a lever, *y*, and the plate *v'* to the long arm of a lever, *y'*. These levers have their fulcrums on pins on the table B, and their arms are connected together, the short arms by the rod *z*, and the long arms by the light spiral spring *t'*. The reciprocating motion imparted to the cross-head E is not uniform, for, owing to the peculiar shape of the cam F, its ascent is much slower than its descent. The movement of the paper over the table is intermittent, owing to the intermittent rotary motion imparted to the drawing-rollers I and J by the eccentric M, arm *h*, shaft L, wheels *i* and *j*, and spring-pawl *g*, the latter turning the shaft K only when it moves in the direction of the arrow, fig. 5. The extent of the movement of the paper is equal to the length of the strip required to form an envelope, and the stoppage in the movement of the paper takes place during the descent of the cross-head. A uniform rotary motion is imparted to the roller Q, which, in conjunction with the pressure-roller P, feeds the proper quantity of paper to the machine; but as the paper traverses intermittently, owing to the intermittent revolving rollers I and J, the latter would at times draw the paper faster than it is fed by the uniformly revolving feed-rollers P.

and Q, and this would result in the tearing of the paper but for the loose fold of the same which is permitted to hang down, as seen in fig. 1, and from which fold the sudden excess of paper demanded by the drawing-rollers is furnished, this excess, being, however, compensated for by an additional supply of paper to increase the loose fold during the stoppage of the drawing-rollers. It is essential that the paper should traverse the table in a direct central course, for any lateral movement of the paper to one side or the other would result in the formation of imperfect and worthless envelopes, or in the tearing of the paper itself. The normal position of the guide plates v and v' is such as to direct the paper in its proper central course, whether there be slight inequalities in the width of the strip or not. Should one edge of the paper, for instance, project slightly beyond its proper limit, and crowd against the plate v so as to move the latter outwards, the opposite plate v' would have a similar and simultaneous movement, thereby making way for the paper, which is thus induced to take a central course, although it may be somewhat wider in some places than others. These automatic guiding plates constitute an important feature in my invention, for if the central line of the paper does not coincide with the proper central line of the course it should traverse, the envelopes would be imperfect and worthless. The arrangement of the knives on the cross-head, and their action on the paper, will be best understood by reference to the diagram, figs. 6 and 8. On the descent of the cross-head the curved knife 2, figs. 1 and 8, severs the paper on the curved line 2, fig. 6, immediately after which, and during the same descent of the cross-head, the blade 3 strikes the paper on the line 3 and thrusts it between the folding rolls T and T', by which the severed strip of paper is reduced to the condition seen in fig. 7, namely, that of an envelope complete, with the exception of the folding and gumming of the flap.

While the cross-head was descending and performing the above duties, other knives had made the incisions 4 4 near opposite edges of the paper, and the superfluous pieces 7 7 had been cut out, leaving the side pieces 8 8 to be folded down and pasted prior to the strip being moved forward, and prior to a second descent of the cross-head, during which the strip previously cut by the knives is severed, and the severed piece folded as described.

It has been deemed unnecessary to illustrate or describe the manner of turning down and pasting the side folds 8 8, as devices similar to those described in the patent granted July 19, 1866, to E. J. Spangler, W. E. Lockwood, and E. D. Lockwood, assignees of Robert Parks, may be used to advantage for these purposes. Prior to my invention, machinery had been used for cutting from a continuous strip of paper envelope blanks of the form described, and folded, as set forth, with but partial success, however, owing to the fact that the different cuts in the paper were accomplished by different devices, operated from one source, but so separated from each other that slight inequalities in the paper, or variations in the same caused by expansion or contraction, or want of unison in the different working parts of the machine, would result in the formation of imperfect blanks and imperfectly folded envelopes. It will be seen that as the cutting and folding blades are arranged only a short distance apart from each other, and on the same cross-head, and perform their respective duties during one and the same movement of the said cross-head, the above objectionable results are avoided.

I claim as my invention, and desire to secure by Letters Patent—

1. Knives attached to one cross-head or plate E, and so arranged as to cut or sever the strip of paper at several points simultaneously, substantially in the manner described, during one movement of the said cross-head.
2. The combination of the said cross-head, its knives, the blade 3, and folding rollers T and T', so that the paper may be cut and folded during one movement of the cross-head.
3. The stationary arm H projecting through an opening in the cross-head E, and carrying rollers I in combination with the rollers J.
4. The combination of the intermittently revolving drawing-rollers F and J with the continuously revolving feed-rollers P and Q, the whole being arranged to act on the paper as set forth.
5. The system of rods x , x' , and x'' , arranged for maintaining the paper in contact with the table, and imparting proper tension to the paper.
6. The guiding plates v and v' , connected together by the system of levers herein described, or the equivalents to the same, and arranged for the proper guidance of the paper in a central course, substantially as described.

In testimony whereof I have signed my name to this specification in the presence of two subscribing witnesses.

JOHN H. COOPER.
